ANTIFOULING DEVICE FOR CATHEADS

Benjamin F. Kelley, Tulsa, Okla.

Application July 24, 1947, Serial No. 763,216

3 Claims. (Cl. 254—176)

1

This invention relates to a rope guide or anti-fouling device for catheads such as are commonly used in connection with well drilling and hoisting equipment.

Conventional catheads employed with well drilling equipment generally consist of a horizontally disposed hollow reeling drum which is mounted on an end of a rotating shaft of the draw works of a drilling rig and is commonly provided with radially extending flanges on the opposite ends of the drum which are integral with and, therefore, rotate with the drum. Such catheads are ordinarily used with a length of rope or cable which is reeled thereon to apply a strain or pull on equipment to be handled about the drilling rig, one end of the rope being attached to the load and the other being coiled around the drum and held by an operator. Such catheads are normally rotated at high speeds and in the absence of suitable precautions or adequate protective measures, the first coil of the rope may become fouled with a succeeding coil and, due to the high speed of rotation of the cathead, may jerk the operator holding the free end of the rope into the mechanism with serious hazard of injury or death.

I have found that one of the principal causes for the fouling of the rope results from the use of the conventional integral flange on the inner end of the cathead against which the pressure of the first coil of the rope is normally exerted. In the normal case, when the first coil of the rope is taken about the cathead and is under load, this coil presses tightly laterally against the integral flange. Since the latter is rotating with the drum, the friction of the rope against the face of the flange causes the rope to "ride" up on the face of the flange, particularly since such flanges normally slope upwardly and outwardly from the surface of the drum. This action tends to pull the first coil radially away from the drum surface and this will often leave sufficient space between the rope and the drum surface for the second coil to slip underneath the first one and so become fouled, with the resulting difficulties and dangers previously referred to.

Existing forms of rope guides or anti-fouling devices for catheads do not take into account the effect of the contact of the first coil with the

2

cathead flange and are, therefore, not completely effective for the purpose intended.

Accordingly, a principal object of this invention is to provide an improved form of anti-fouling device for catheads.

An important object is the provision of an anti-fouling device which includes a stationary flange surrounding the rotating cathead drum for receiving the lateral pressure of the cathead rope.

Another object is the provision of an anti-fouling device which includes a stationary flange surrounding the rotating cathead drum and a novel form of rope guide carried by the flange for effectively separating the first and second coils of the cathead rope on the drum.

Other and more specific objects and advantages of this invention will become apparent from the following detailed description when read in conjunction with the accompanying drawings which illustrate one useful embodiment in accordance with this invention.

In the drawings:

Fig. 1 is a longitudinal sectional view of a cathead and anti-fouling device in accordance with an embodiment of this invention, the view being taken generally along line 1—1 of Fig. 2;

Fig. 2 is a cross-sectional view taken along line 2—2 of Fig. 1;

Fig. 3 is a perspective view of the structure in accordance with an embodiment of this invention;

Fig. 4 is a projected plan view of one of the elements of the anti-fouling device; and

Figs. 5, 6 and 7 are cross-sectional views along lines 5—5, 6—6 and 7—7, respectively, of Fig. 2, of the element shown in projected plan view in Fig. 4.

Referring to the drawings, the numeral 10 designates a conventional horizontally disposed shaft forming a part of the usual well drilling draw works, which is rotatable by suitable drive mechanism, not shown, which is a part of the drawworks mechanism. A hub 11, having a peripheral flange 12, is mounted on the end of shaft 10 and is keyed thereto so as to rotate with the shaft. Jam nuts 13, screwed on the outer end of the shaft hold hub 11 on the end of the shaft. A hollow tubular cathead drum 14 is telescoped over the end of shaft 10 and is provided at its inner end with an inwardly extending

flange 15 which seats against flange 12 when the drum is in place. Cap screws 16 extend through both flanges and serve to fasten drum 14 rigidly on hub 11. The outer end of drum 14 carries the usual outwardly flaring integral flange 11. With the described arrangement, drum 14 and hub 11 form a unitary structure which is locked to shaft 10 and rotatable thereby. A clutch plate 18 is shown mounted on the inner end of hub 11 and locked to flange 12 by means of pins 19 to form the driving element of a clutch mechanism, not shown, and which forms no part of the present invention. Numeral 20 indicates a portion of a tubular guard which is designed to enclose and shield the clutch mechanism and its connected elements (not shown). The outer end of guard 20 is provided with an annular end plate 21 which has a hollow central hub 22 which closely surrounds the inner end of drum 14 and serves as a journal therefor. A sleeve bearing 23 annularly disposed between hub 22 and flange 12 of hub 11 provides an anti-friction surface for rotation of drum 14 relative to plate 21, which is, of course, stationary. It will be understood that plate 21 need not be a part of guard 20 but may be affixed to any stationary portion of the drawworks structure or any other adjacent stationary structure.

The outer face of plate 21 has mounted thereon an arcuate abutment 24 which closely surrounds an arcuate segment of the drum surface immediately adjacent the outer face of plate 21. Abutment 24 extends circumferentially about drum 14 through an arc which normally is greater than 90 degrees, and in most cases, for about 135 to 145 degrees. Abutment 24 also increases progressively in thickness, that is, in the dimension parallel to the axis of the drum, in the direction of rotation of the drum (See Figs. 4, 5, 6 and 7 particularly). The maximum thickness of abutment 24 at one end will normally be slightly greater than the diameter of the rope to be wound on the drum and will taper gradually down to zero thickness at its opposite end where it merges smoothly with the surface of plate 21. Abutment 24 will normally be cast integrally with plate 21 but may, of course, be separately cast or machined and affixed to the face of plate 21 in any conventional manner, as by welding, for example. Abutment 24 is termed by me a "rope crowder" and functions to direct the first coil of the rope R, (see Figs. 1 and 3 particularly) into its proper helix, so that the rope, entering from in front of and underneath drum 14, will be progressively crowded outwardly from plate 21 over the drum surface and will thereby be prevented from becoming fouled at the point where the rope, in beginning its second coil, passes the first coil on the drum. Since, as noted previously, plate 21 is stationary, there will be no tendency for the first coil of the rope to "ride" up and out on the face of the plate when under load and the danger of fouling is thereby further decreased.

The point of entry of the rope upon drum 14 may vary angularly rather widely between the horizontal and vertical directions. In order to further assure complete separation of the first and second coils irrespective of the angle at which the rope enters upon the drum, a flat flexible steel finger 25, of arcuate form, is provided as a further extension of abutment 24. Finger 25 has one end rigidly connected to the enlarged end of abutment 24 by means of countersunk screws 26 and is normally seated in a suitable recess 27 cut in the outer face of abutment

24 to a depth, as measured parallel to the axis of the drum, such that the outer face of finger 25 will be flush with the outer face of abutment 24. The inner face of recess 27 against which finger 25 is seated is made parallel to the face of plate 21 so that finger 25 will extend parallel to the face of plate 21 rather than continue at the same angle at which abutment 24 diverges from the face of the plate. The arcuate length of finger 25 will normally be greater than 90 degrees, so that the total arc covered by both abutment 24 and finger 25 will substantially exceed 180 degrees and preferably 270 degrees or more. In any event, the total length of abutment 24 and finger 25 and their angular position about drum 14 will normally be such that the free end of finger 25 will extend past the point at which the second coil of the rope passes the point of entry of the rope on the drum surface and will thereby assure complete separation of the first and second coils of the rope.

An upwardly turned hook element 28 extends outwardly from plate 21 below drum 14 and serves as a rest or support for the load end of the rope when not in use.

From the foregoing, it will be seen that the anti-fouling device in accordance with this invention comprises a stationary plate surrounding the inner end of a cathead and is combined with a novel form of rope guide and divider for cathead ropes to assure complete separation of the first and second coils of a cathead rope and to thereby effectively prevent fouling of the rope as it is reeled on the cathead drum at conventional high speeds.

It will be understood that various alterations and changes may be made in the details of the illustrative structure without departing from the scope of the appended claims but within the spirit of this invention.

What I claim and desire to secure by Letters Patent is:

1. In catheads including a rotatable cathead drum and a rope to be wound thereon, an anti-fouling device, comprising, a stationary plate member annularly surrounding said drum adjacent an end thereof about which the initial turns of said rope are wound, and an arcuate abutment integral with the face of said plate member facing the winding surface of said drum, said abutment encircling a portion of the circumference of said drum and increasing progressively in lateral thickness in the direction of rotation of said drum.

2. In catheads including a rotatable cathead drum and a rope to be wound thereon, an anti-fouling device, comprising, a stationary plate member annularly surrounding said drum adjacent an end thereof about which the initial turns of said rope are wound, an arcuate abutment integral with the face of said plate member facing the winding surface of said drum, said abutment encircling a portion of the circumference of said drum and increasing progressively in lateral thickness in the direction of rotation of said drum, and an arcuate finger element extending from the enlarged end portion of said abutment substantially parallel to and spaced from said plate member for a major portion of the remaining portion of the drum circumference.

3. In catheads including a rotatable cathead drum and a rope to be wound thereon, an anti-fouling device, comprising, a stationary plate member annularly surrounding said drum adjacent an end thereof about which the initial turns

of said rope are wound, an arcuate abutment integral with said plate member encircling a portion of the circumference of said drum and diverging from the face of said plate member in the direction of rotation of said drum to form a helical guiding surface for the first turn of said rope about said drum, and a flexible metal finger element extending from the larger end of said abutment circumferentially of said drum and parallel to and spaced from the adjacent surface of said plate member.

10 BENJAMIN F. KELLEY.
